Derrel Barnes
ATTORNEY

UNITED STATES PATENT OFFICE.

ERNEST TALBOT AND NAPOLEON CAMPBELL, OF SEATTLE, WASHINGTON.

SHINGLE-BOLT-SAWING MACHINE.

1,362,576.

Specification of Letters Patent. Patented Dec. 14, 1920.

Application filed December 26, 1919. Serial No. 347,349.

To all whom it may concern:

Be it known that we, ERNEST TALBOT and NAPOLEON CAMPBELL, citizens of the United States, residing at Seattle, in the county of King and State of Washington, have invented certain new and useful Improvements in Shingle-Bolt-Sawing Machines, of which the following is a specification.

This invention relates to wood-sawing machines and more particularly to that class known as bolting and sapping machines.

The object of our invention is the improvement in machines of this character whereby the work may be more expeditiously and inexpensively accomplished than hitherto.

The invention consists in the novel construction, arrangement and combination of parts as will be hereinafter described and claimed.

In the accompanying drawings, Figure 1 is a plan view of a shingle-bolting and sapping machine embodying our improvements. Fig. 2 is a longitudinal vertical section through 2—2 of Fig. 1. Fig. 3 is a transverse sectional view taken substantially through 3—3 of Fig. 1; and Fig. 4 is an end elevational view of the right hand end of Fig. 3, with the roller retaining ring removed.

In said drawings, the reference numerals A and B designate endless conveyer chains passing about sprocket wheels 21 and 22 mounted upon a transverse shaft 23 adjacent to one end of the machine and sprocket wheels 31 and 32 mounted upon a transverse shaft 33 adjacent to the other end of the machine. The upper leads of said chains are guided for travel to have their top surfaces in a horizontal plane by being supported in channel bars 4 which are themselves supported by transverse beams 41 which, in turn, are supported by sill members 42 and constitute therewith the frame of the machine.

The shafts 23 and 33 are driven by trains of gears, each train including spur wheels 51, 52 and friction wheels 53, 54 through the medium of an intermediate shaft 55 from a shaft 56 which is driven by means of a power belt (not shown) passing about a pulley 57 upon the respective shaft 56.

Said trains of gears are driven to cause the associated shafts 23 and 33 to be rotated normally in the directions indicated by arrows α and γ , respectively, in Fig. 2.

The shafts 23 and 33, may, however, be ro-

tated oppositely to those denoted by the respective direction arrows by disconnecting the spur wheels 51 from the respective shafts. For which purpose, by preference, we make a wheel 51 shown in Figs. 3 and 4, with an outer rim 51¹ having a central bore to receive a circular spider 51² whose hub is keyed to the respective shaft. In the periphery of said spider is provided a plurality of substantially triangular recesses 51³ which accommodate balls or rollers 51⁴ which serve to engage the spider to the rim when the latter is rotated as indicated by arrow c in Fig. 4 but allow the rim 51¹ to rotate independently of the spider in the opposite direction. The above described means for releasably coupling a rim and spider is, in itself, not new and its operation is obvious.

The sprocket wheels 21 and 32 are keyed or otherwise secured to the shafts 23 and 33. The other sprocket wheels 22 and 31 are keyed or integral with sleeves 24 and 34 which are rotatable upon the above referred to shafts. Formed with or secured to ends of said sleeves are members 25 and 35 of jaw clutches whose complementary sliding members 26 and 36 are splined to the respective shafts and are shiftable by means of forked levers 27 and 37 into or out of engagement with their companion members to accordingly couple or uncouple the sleeves 24 and 34 and the associated sprocket wheels 22 and 31 with or from the respective shafts. In order to regulate the sliding clutches in unison so that one of them will be disengaged prior to the other one being engaged we employ a connecting rod 6 between the levers 27 and 37. An arm, as 38, of one of said levers may be extended to within convenient reach of the operator for regulating the clutches.

8 represents a circular saw rotatable in a plane between the A and B sets of conveyer chains, said saw being mounted on an arbor 100 7 which is journaled in boxes 71 of a hanger frame 72 and driven by a power belt, not shown, passing about the arbor pulley 73.

In operation, a block is placed upon end on chains A and B in front of the saw S 105 and by actuating all of the sprocket wheels 21 and 22 on shaft 23 the block is fed by the chains in the direction of arrow d , Fig. 2, against and by the saw to effect the removal of a slab of sap wood from the block 110 or the cutting of the block into bolts.

By rendering the power inoperative with

- respect to shaft 23 and actuating the shaft 33, with the sleeve 34 coupled to the latter, both parts of the block thus sawed may be returned to the right hand end of the machine; or by having the sleeve disengaged, but one part may be returned. By placing a block upon both sets of chains A and B and operating them in opposite directions a block can be most conveniently turned.
- 10 When a bolt has been cut from a block it may be discharged from a selected end of the machine by causing either set of chains, A or B, to be suitably actuated while the other set remains idle or is operated to feed 15 a block to and by the saw for removing thereby a slab from such block.

What we claim, is—

1. In a bolt-sawing machine, the combination with a vertical saw, of bolt feeding devices provided at opposite sides of the saw, and means to cause said devices to travel simultaneously in the same or opposite directions.
2. In a bolt-sawing machine, the combination with a saw, of a set of power actuated feeding devices at each side of the saw, said devices being arranged to have both sets thereof actuated for passing bolts against and by the saw and also in a reverse direction thereto.
3. In a bolt-sawing machine, the combination with a saw, of a bolt carrier provided at each side of the saw, means to impart motion selectively to one or both of said carriers to feed bolts to and by the saw.
4. In a bolt-sawing machine, the combination with a saw of a bolt carrier provided at each side of the saw, means to impart feeding motion to both of said carriers for conveying a bolt to and by the saw, and means whereby one of said carriers is caused to travel in a reverse direction independently of the other carrier.
5. In a bolt-sawing machine, two sets of

endless feed chains, means to drive both sets of said chains, operative connections between said means and each set of chains in bolt feeding direction or in a reverse direction selectively, and means for regulating the aforesaid connections whereby the two sets of chains are simultaneously driven in opposite directions.

6. In a bolt-sawing machine, the combination with the machine frame, and a circular saw disposed intermediate the length of said frame, of feed devices consisting of a set of conveyer chains at each side of the saw, sprocket wheels for said chains, shafts adjacent to each end of the frame for said sprocket wheels, means for releasably connecting the sprocket wheels for one set of chains to one of said shafts and the wheels for the other set to the other shaft selectively, and power actuated means to drive the shafts in opposite rotary directions. 65

7. In a bolt-sawing machine, the combination with the machine frame, and a circular saw disposed intermediate the length of said frame, of feed devices consisting of a set of conveyer chains at each side of the saw, 70 sprocket wheels for said chains, shafts adjacent to each end of the frame for said sprocket wheels, means for releasably connecting the sprocket wheels for one set of chains to one of said shafts and the wheels 75 for the other set to the other shaft selectively, power actuated means to drive the shafts in opposite rotary directions, and devices included in the last named means for rendering the respective shafts rotatable independently of the driving means therefor. 80

Signed at Seattle, Washington, this 16th day of December, 1919.

ERNEST TALBOT.

NAPOLEON CAMPBELL.
